UNITED STATES PATENT OFFICE.

WALTER F. SMITH, OF NEW BEDFORD, MASSACHUSETTS, ASSIGNOR TO THE PAIRPOINT MANUFACTURING COMPANY, OF SAME PLACE.

DESIGN FOR A COFFIN-PLATE.

SPECIFICATION forming part of Design No. 21,111, dated October 13, 1891.

Application filed July 9, 1891. Serial No. 398,974. Term of patent 7 years.

To all whom it may concern:

Be it known that I, WALTER F. SMITH, of New Bedford, in the county of Bristol and State of Massachusetts, have invented and 5 produced a new and original Design for Coffin-Plates, of which the following is a specification, reference being had to the accompanying drawings, forming part thereof.

Figure 1 is a plan, and Fig. 2 an edge view, 10 of one shape of plate containing my design, these two views being deemed necessary to fully illustrate my design.

The leading feature of my design consists 15 in a raised face portion formed with a cross-wise-fluted flange extending around the body

part and being in a different plane from the face.

A is the face portion, and A' is the flange, which is fluted crosswise at a a' throughout its entire extent. The flange A' is in a different plane from the face A. The face portion is formed with a shoulder b intermediate the flange and body part A.

I claim—

The design for a coffin-plate, as herein described and shown.

WALTER F. SMITH.
